SCRAPER TOOL

Guy N. Wetzel, 1040 S. Roosevelt Ave.,
Bexley, Ohio 43209

Filed Feb. 15, 1971, Ser. No. 15,911

Term of patent 14 years

Int. Cl. D8—05

U.S. Cl. D49—23

FIG. 1 is a perspective view of a scraper tool showing my new design;

FIG. 2 is a side elevational view;

FIG. 3 is an end elevational view; and

FIG. 4 is a similar view looking toward the opposite end of the scraper tool.

I claim:

The ornamental design for a scraper tool, substantially as shown.
